(57) **CLAIM**

The ornamental design for a faucet bridge, as shown and described.

DESCRIPTION

FIG. 1 is a perspective view of a faucet bridge showing my new design;

FIG. 2 is a first side view thereof, the opposite side being a mirror image of the side shown;

FIG. 3 is a front elevational view thereof;

FIG. 4 is a top plan view thereof; and,

FIG. 5 is a bottom view thereof.

The broken lines showing portions of a faucet are included for illustrative purposes only and form no part of the claimed design.
